W. F. CLARK

CONTROLLING DEVICE

Filed June 7 1919

Patented Nov. 25, 1924.

UNITED STATES PATENT OFFICE.

WARREN F. CLARK, OF CLEVELAND, OHIO, ASSIGNOR, BY MESNE ASSIGNMENTS, TO AUTOMATIC ELECTRIC HEATER COMPANY, OF WARREN, PENNSYLVANIA, A CORPORATION OF DELAWARE.

CONTROLLING DEVICE.

Application filed June 7, 1919. Serial No. 302,401.

To all whom it may concern:

Be it known that I, WARREN F. CLARK, a citizen of the United States, residing at Cleveland, in the county of Cuyahoga and State of Ohio, have invented a certain new and useful Improvement in Controlling Devices (C), of which the following is a full, clear, and exact description.

The present invention relates to a device for controlling an electric heating coil in accordance with temperature conditions existing in the device, being heated by the coil.

One object of the invention is to provide a device for the purpose which is very sensitive so that it responds readily to temperature conditions.

A further object is to provide a device for the purpose which upon repeated continued action undergoes no changes which would cause it to become inactive as is frequently the case with thermostats working upon the principle of expansion and contraction.

A further object is to provide a construction in which a confined fluid creates a pressure condition in accordance with the degree to which it is heated and a pressure responsive contact operated or moving device which is operated under predetermined pressure conditions of the fluid. An additional object is to provide an electrically heated device with which there is associated a closed receptacle containing a fluid, which receptacle is suitably connected with a pressure responsive device, such as a Bourdon tube, which tube is operatively connected with a pair of electrical contacts which control the circuit of which the electrical heating element is a part so that the current is supplied to the heating coil at such times as are necessary to maintain the device being heated by the coil at a predetermined temperature.

Generally speaking, the invention may be said to comprise the elements and the combinations thereof set forth in the accompanying claims.

Reference should be had to the accompanying drawings forming a part of this

specification in which Fig. 1 is a vertical section through an electrically heated device showing the regulator; Fig. 2 is an elevation with portions in section showing the controlling device; Fig. 3 is a diagram showing an electric circuit concluding the heating coil, which is to be controlled.

Referring to the drawings, 1 indicates a container which in the present instance is a pipe like section which at its upper end is threaded and adapted to receive a hollow table, which is indicated at 2. The interior of the member 1 communicated with the interior of the table. In the construction illustrated, the member 1 is intended to function as a steam generator and the steam generated is supplied to the interior of the member 2 which keeps the member 2 in a predetermined heated condition, the member 2 serving as a hot plate and may be utilized in various manners.

Surrounding the member 1 is an electrical coil 3. This coil is imbedded in a body of heat insulating material 4, which serves not only as a support for the coil, but as before indicated, serves to prevent radiation of heat from the electric coil 3 so that the heat of the coil is delivered to the member 1 and the water contained therein.

The lower end of the member 1 receives a cap 5 which has a central opening adapted to receive a threaded bushing 6, this bushing has a central opening. Within the member 1 there extends a closed container 7 which is adapted to contain a fluid which when heat volatilizes or vaporizes thereby creating a pressure condition within the member 7.

Communicating with the interior of the container 7 is a small tube 8, and surrounding the tube 8 is another tube 9, which is secured to the exterior of the receptacle 7 in a desired manner and the tube 7 extends through the central opening in the bushing 6. The tube 9 is secured with respect to the bushing 6 and this may be conveniently accomplished by brazing the tube 9 to the bushing 6.

The tube 9, as before stated, extends upon the outside of the tube 8, forming a protecting casing for the small tube 8 which might

otherwise become damaged. The tube 9 is secured to a nipple 10 which is carried by a casing 11, which casing contains a Bourdon tube 12. The tube 9 is sealed at the 5 end where it connects with the nipple 10 so that the only communication between container 7 and the Bourdon tube is through the tube 8. The Bourdon tube, as is well known, is hollow and one end of it is secured to 10 the nipple 10. The pipe 8 communicates with the interior of the Bourdon tube so that the interior of the receptacle 7 communicates with the interior of the Bourdon tube 12 through a small pipe 8.

15 The casing 11 contains a chart 11^a and cooperating with the chart is a pointer 13 which is carried upon a shaft 14 which shaft by suitable means is connected with the free end of the Bourdon tube so that movement of the tube causes movement of the pointer. This construction forms no part 20 of the present invention. A further description thereof is unnecessary.

Associated with the casing 11 is another 25 casing 11^b within which there is mounted a pair of contacts 15 and 16, one of these contacts is mounted upon a resilient member 17 and cooperating with the resilient member 17 is a pin 18 which is carried by the 30 free end of the Bourdon tube, expansion of the Bourdon tube will therefore cause the pin to engage with a resilient member thereby moving the contacts apart.

The position of the contacts with respect 35 to the pin may be varied by adjusting the position of the contacts so as to require more or less movement of the end of the Bourdon tube in order to effect engagement of the resilient member by the pin and 40 consequent separation of the contacts.

As shown in Fig. 3, the circuit which energizes the heating coil 4 is controlled by the contacts and when the contacts are in engagement, the circuit is closed so that the 45 coil 3 is energized and vice versa, when the contacts are separated the coil is not energized.

If we assume that the container 1 has a suitable quantity of water therein and that 50 the container and water are being heated by the electric coil 3, it will be very clear that the container 7 and its contents will be subject to the heat conditions within the member 1, this will cause the fluid within the 55 container 7 to expand and exert a pressure condition which is communicated to the interior of the Bourdon tube, thereby causing the tube to expand and ultimately to effect relative movement between the contacts for the purpose of breaking the circuit which supplies electric current at the coil 3.

By adjusting the position of the contacts with respect to the Bourdon tube determines the degree of movement which the Bourdon 60 tube shall have before moving the contacts

apart and the movement of the Bourdon tube is in turn controlled by the pressure condition within the container 7, therefore it will be apparent that the position of the contacts may be so adjusted as to cause the 70 energizing circuit for the heating coil 3 to be broken in accordance with any predetermined pressure condition within the member 1 and it will of course be understood that the pressure is directly proportional to the temperature. 75

From the foregoing it will be seen that the device may be adjusted so as to substantially maintain a constant temperature condition within the member 1, the circuit 80 of the coil 3 being broken when the predetermined temperature condition is reached or exceeded and the electric current again being supplied to the coil 3 when the temperature condition drops below the predetermined temperature. In the present instance I have shown and described a particular construction which the controlling device assumes, but I do not thereby wish 85 to limit myself except as defined in the 90 claims.

Having described my invention, I claim—

1. In a device of the character described, a closed receptacle, a fluid contained therein, a Bourdon tube, means connecting the Bourdon tube with the interior of the receptacle, a pair of contacts normally having a fixed position with respect to each other and one of which is resiliently mounted, means carried by the Bourdon tube for moving one of said contacts with respect to the other. 100

2. In a device of the character described, a closed receptacle, a fluid within said receptacle, a casing, a Bourdon tube within 105 said casing, a tubular member connecting the said casing with the receptacle, a second tube within the first mentioned tube for connecting the interior of the receptacle with the Bourdon tube, a pair of contact members which normally occupy a fixed relation with respect to each other one of which is resiliently mounted, means carried by the Bourdon tube for moving one of 110 said contacts with respect to the other. 115

3. In a device of the character described, the combination with a container, a receptacle within the container, a tubular member connected with the receptacle and extending upon the outside of the container, 120 a bushing through which the said tubular member extends, a Bourdon tube, means connecting the Bourdon tube with the interior of the receptacle, a pair of contacts, which contacts are connected with the moving coil, and means carried by the Bourdon tube for moving one of the contacts with respect to the other, one of said contacts being resiliently mounted. 125

4. In a device of the character described, 130

a container, a receptacle within the container, a tube connected with the receptacle, a closure member for the container through which said tubular member extends, a casing connected with the said tubular member, a Bourdon tube within the casing, means for connecting the tubular member with the interior of the receptacle, a pair of contacts connected with the heating coil and means carried by the Bourdon tube for 10 moving one of said contacts with respect to the other, said contacts being adjustable with respect to the moving means carried by the Bourdon tube.

5 In testimony whereof, I hereunto affix 15 my signature.

WARREN F. CLARK.
